UNITED STATES PATENT OFFICE.

FREDERICK E. TURNER, OF KANSAS CITY, MISSOURI, ASSIGNOR TO KANSAS CITY ELEVATOR MANUFACTURING COMPANY, OF KANSAS CITY, MISSOURI, A CORPORATION OF MISSOURI.

SAFETY MECHANISM FOR ELEVATORS.

1,249,860.

Specification of Letters Patent. Patented Dec. 11, 1917.

Application filed December 20, 1916. Serial No. 138,079.

To all whom it may concern:

Be it known that I, FREDERICK E. TURNER, a citizen of the United States, residing at Kansas City, in the county of Jackson and State of Missouri, have invented certain new and useful Improvements in Safety Mechanism for Elevators; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to safety mechanism for elevators and more particularly for elevators of the corner lift type, the principal object of the invention being to utilize the unequal strain occasioned by breakage of one of the supporting cables for actuating the safety mechanism.

It is also an object of the invention to effect operation of the safety mechanism from a governor, whereby descent of the elevator may be interrupted should it travel beyond a predetermined speed.

In accomplishing these objects I have provided improved details of structure, the preferred forms of which are illustrated in the accompanying drawings, wherein:

Figure I is an inverted perspective view of an elevator platform, illustrating the safety mechanism.

Fig. II is a side view of the platform and the safety mechanism.

Fig. III is a longitudinal, vertical section of the same.

Fig. IV is an end view of the platform trip mechanism.

Fig. V is a transverse section on the line V—V, Fig. II.

Fig. VI is a transverse section on the line VI—VI, Fig. II, particularly illustrating the governor mechanism.

Fig. VII is a detail view of a guide block and clutch.

Fig. VIII is a section on the line VIII—VIII, Fig. VII, particularly illustrating the mounting of the clutch shaft on the guide block.

Fig. IX is a detail perspective view of one of the trip levers.

Fig. X is a detail perspective view of one of the clutch and guide sets.

Fig. XI is a detail perspective view of the governor control lever.

Referring more in detail to the drawings:

1 designates an elevator platform which may be of ordinary wood or metal construction, comprising end beams 2—2', side beams 3—3' and a floor 4, and which is suspended between corner guide posts 5 in the elevator shaft by cables 6 that hang from a suitable winding mechanism (not shown).

Secured to the under side of the platform, near the ends and center thereof, are cross beams 7—7—7" on which the clutch mechanism, presently described, is mounted and fixed to the outer ends of the beams 7 and 7" are blocks 8, comprising spaced flanges 9—9' forming outwardly opening channels 10 for slidably receiving the guide posts 5.

Extending between opposite blocks 8 at each end of the platform and journaled at 75 its ends in spaced wings 11—11' formed integrally with each of the blocks, is a cross shaft 12 and mounted on said shafts between the wings of the blocks are clutch members 13 (Figs. VII, VIII and X) each of which 80 has a tooth 14 adapted, when its member 13 is turned, to project inwardly through a slot 15 in the adjacent flange 9' to engage the guide posts 5 and effect a seat thereon to stop the platform in its descent.

In the present device the shafts 12 are preferably square in cross section to effect a substantial mounting for the grip members and are seated at their ends in collars 16 which in turn are revolvably mounted in 90 the block flanges 11—11' at opposite sides of the clutch members 13.

Pivotedly mounted in brackets 17 at opposite corners of the platform, adjacent the guide blocks 8, are crank levers 18 (Fig. 95 IX) each of which comprises a downwardly extending arm 18' and an outwardly extending arm 18", the arms 18' of each of the opposite end pairs of levers being connected by cross bars 20 to hold the arms 18" in 100 substantially horizontal position, the horizontal arms 18" being provided with seats

21 adjacent their outer ends for receiving bolts 22 which extend upwardly through the floor of the platform and are provided, at their upper ends with eyes 23 to which the 5 supporting cables 6 are attached.

Mounted longitudinally beneath the center of the platform to overlie the cross bars 29 and revolubly supported at its ends and at an intermediate point in bearings 26 is a 10 shaft 27. Mounted on said shaft adjacent its ends, are laterally directed rocker arms 28, each provided at its free end with a roller 29 (Fig. V) which rides on a rocker plate 30 on a relative cross bar 20. Each of the 15 rocker plates comprises spaced and oppositely inclined faces 31—31', one of which will engage a roller 29 upon movement of the rocker plate in either direction and cause the arm 28 to be raised at its outer end to 20 partially revolve the shaft 27.

Also mounted at each end of the shaft 27 is a laterally extending arm 33 the outer end of which is adapted to underlie the outer end of a rocker bar 34 on the adjacent clutch 25 connecting shaft 12. The inner ends 35 of the bars 34 extend beyond the clutch shafts and attached to said ends and to the under side of the platform 2 are coil springs 36 whereby the clutch shafts are yieldingly 30 held in such position that the clutches thereon are yieldingly held away from and do not engage the guide posts 5.

By so constructing the rocker levers, it will be seen that the platform is held in balanced suspension by the supporting cables, and that should any one of the cables break, the tension of the opposite cable will cause the crank lever to be rocked in its mounting and the cross bar 20 moved toward one side 40 of the platform, movement of the cross shaft in either direction causing an inclined face of the rocker plate to engage the roller 29 to raise the arm 28 and cause a partial revolution of the longitudinal shaft 27.

45 Revolution of the shaft 27 causes the outer ends of the arms 33 to engage the bars on the clutch shafts 12 so that the bars are raised to rock said shafts, forcing the teeth of the clutch members to grip the guide 50 posts 5 and stop the platform.

Pivottally mounted at one end of the center cross plate 7' is a crank lever 40 (Fig. VI) having an outwardly extending arm 41 and a downwardly extended arm 42, and 55 connected with the lower end of the arm 42 and with an arm 43 on the shaft 27 is a link 45 whereby rocking of the crank lever will cause a rotation of the shaft 27 to effect a grip on the guide rails as previously described.

Attached to the arm 41 is a cable 46 which extends upwardly and about a governor drum 47 in such a manner that as the car descends the drum is revolved; the governor 65 arms 48 being so arranged that excessive

speed will cause the latter to spread sufficiently to engage stops 49 to interrupt movement of the governor.

Presuming the governor to be so attached, should the platform arms drop suddenly, the 70 governor arms will be thrown outwardly to engage the stops 49 to stop movement of the drum 47, causing a sudden tension on the cable 46 which will rock the crank lever 40 and revolve the shaft 27, in this manner 75 throwing the clutches to prevent a further fall of the platform.

By so constructing the parts it will be seen that should any one of the cables break, or should an operator lose control of the 80 hoisting motor, so that the elevator might drop suddenly, all the clutches will be automatically and simultaneously thrown to grip the guides and prevent the elevator from falling, and that the elevator platform may 85 be supported by the guides and clutches until properly repaired or controlled.

Having thus described my invention what I claim as new therein and desire to secure by Letters-Patent, is:—

90 1. The combination with an elevator platform, of paired rocker members on the platform, a link connecting said rocker members, cables connected with the rocker members to support the platform, paired clutch members on the platform, a shaft operably connected with said clutch members, a rock shaft, means on the connecting link for actuating the rock shaft, and means operable by the rock shaft for actuating the 95 clutch shaft.

2. The combination with an elevator platform, of paired rocker members on the platform, a link connecting said rocker members, cables connected with the rocker members to support the platform, paired clutch members on the platform, a shaft operably connected with said clutch members, a rock shaft, a cam on the connecting link, means operable by the cam for actuating the rock 105 shaft, and means operable by the rock shaft for actuating the clutch shaft.

3. The combination with an elevator platform, of paired rocker members on the platform, a link connecting said rocker members, cables connected with the rocker members to support the platform, paired clutch members on the platform, a shaft operably connected with said clutch members, a rock shaft, a cam on the connecting link, means operable by the cam for actuating the rock 115 shaft, a rock bar on the clutch shaft, and means on the rock shaft for actuating said rock bar.

4. The combination with an elevator platform, of paired rocker members on the platform, a link connecting said rocker members, cables connected with the rocker members to support the platform, paired clutch members on the platform, a shaft 120 125

130

operably connected with said clutch members, a rock shaft, a cam on the connecting link, means operable by the cam for actuating the rock shaft, a rock bar on the clutch shaft, means on the rock shaft for actuating said rock bar, and yielding means for holding the clutch shaft in idle position.

5. The combination with an elevator platform, of paired rocker members on the platform, a link connecting said rocker members, cables connected with the rocker members to support the platform, paired clutch members on the platform, a shaft operably connected with said clutch members, a rock shaft, a cam on the connecting link, means operable by the cam for actuating the rock shaft, a rock bar on the clutch shaft extending from opposite sides of the clutch shaft, an arm on the rock shaft 15 for engaging one end of said rock bar, and a spring connected with the opposite end of the bar to yieldingly retain the clutch shaft in idle position.

6. The combination with an elevator platform, of paired rocker members at opposite sides of the platform, a link connecting said rocker members, cables connected with the rocker members to support the platform, paired clutch members at opposite sides of

the platform operable independently of the 30 rocker members, a shaft operably connected with said clutch members, a rocker shaft arranged transversely of the connecting link and clutch shaft, means on the connecting link and rock shaft for rotating the shaft 35 upon longitudinal movement of the link and means on the rock shaft and clutch shaft for rotating the clutch shaft upon rotary movement of the rock shaft, for the purpose set forth.

7. The combination with an elevator platform, of paired rocker members at opposite sides of the platform, transverse connecting links connecting the rocker members, cables connected with the rocker members to support the platform, paired clutch members at the opposite sides of the platform, a shaft operably connecting said clutch members, a rock shaft extending longitudinally relative to the platform, means on the rock shaft and link for rotating the rock shaft upon longitudinal movement of the link, an arm on the clutch shaft and an arm on the rock shaft 45 for engaging the clutch shaft arm to rock the latter upon movement of the former.

In testimony whereof I affix my signature. 55

FREDERICK E. TURNER.
